UNITED STATES PATENT OFFICE.

WASIL PAZAYCHUK AND WASYL PATZ, OF NEW CASTLE, DELAWARE.

ANTISUBMARINE DEVICE.

1,302,206.

Specification of Letters Patent. Patented Apr. 29, 1919.

Application filed April 18, 1918. Serial No. 229,357.

To all whom it may concern:

Be it known that I, WASIL PAZAYCHUK, a citizen of Ukraine, residing at New Castle, county of New Castle, and State of Delaware, and I, WASYL PATZ, a citizen of Ukraine, residing at New Castle, county of New Castle and State of Delaware, have invented certain new and useful Improvements in Antisubmarine Devices, of which the following is a specification

This invention relates to improvements in anti-submarine devices, and particularly to types adapted to ward or fend off submarines or other under-sea projectiles.

The principal object of the invention is to provide a plurality of rigidly supported resilient armor plates, arranged to encircle the entire hull of a ship, whereby injury is prevented from being done the same.

A further object is to provide a novel form of resilient supporting means, so that the armor plates may retract under the impact of a blow, cushioning the effect of the same with respect to the ship to which they are engaged.

These and other like objects are attained by the novel construction and combination of parts hereinafter described and shown in the accompanying drawings, forming a material part of this disclosure, and in which:

Figure 1 is a fragmentary perspective view showing a conventional type of ship and the application of the invention.

Fig. 2 is a top plan view, showing a ship and the manner of applying the invention.

Fig. 3 is an enlarged fragmentary side elevational view of the same, and

Fig. 4 is a further enlarged fragmentary horizontal sectional view, taken through the armor supports.

Engaged with the exterior of the ship's hull, are a plurality of horizontal outstanding rigid bars 14, the same supporting an armor plate 15, extending circumjacently around the entire hull of the ship, and which forms the inner protective guard therefor.

The outer guard plate elements 18 adapted to receive the impact, are rectangular in outline and arranged in rows as indicated.

Secured to the exterior of the plate 15, are rigid tubular elements 20, similar, but smaller tubular elements 22, being rigidly affixed upon the inner side of the guard plates 18, and adapted to operate telescopically within the rigid tubular elements 20.

Formed in the tubular elements 20, upon opposite sides thereof, are open longitudinal slots 23, adapted to receive the out-turned, hook-like prongs 24, of lugs formed with the inner tubes 22, into which extend longitudinal shaped recesses 25, from their outer ends so that the tubes will operate in the manner of springs, permitting insertion of the prongs 24 into the slots 23, the prongs 24 acting as limit stops for the amount of movement of the tubes 22, within the engaging tubes 20, and preventing them from being pressed outwardly beyond a definite distance by the coiled compression springs 27, which encircle both of the tubular elements and are adapted to press the plates 18 strongly outward from the inner plates 15.

Thus a double protection for the ship is provided, first, by the resiliently supported outer plates 18 which are in themselves adapted to receive the impact of a projectile or the like, and second, by the inner rigid plates 15, thereby preventing damage and it will be readily understood that the plates 18 at the bow or stern of the vessel must be bent in accordance with the contour of the ship, while the supporting elements remain substantially as described.

Having thus described our invention what we claim as new and desire to secure by Letters Patent, is.

1. In an anti-submarine device, the combination with the hull of a ship and a plurality of rigid bars extending horizontally outward therefrom, of an integral armor plate adjacent to the hull of said vessel, engaged with the ends of said bars, a plurality of tubular elements secured to the exterior of said rigid armor plate, a plurality of independent rectangular armor plates, tubular elements engaged upon the inner sides thereof, said tubular elements being telescopically receivable within the first named tubular elements, means for limiting the motion of said second tubular elements, and a plurality of springs encircling both of said tubular elements, whereby said movable plates are extended normally outward.

2. In an anti-submarine device, the combination with a fixed guard plate adjacent to the hull of a vessel, of a plurality of tubes secured upon the outer side of said fixed plate, said tubes containing longitudinal slots, a plurality of independently movable, rectangular armor plates, tubes engaged upon the inner side thereof, said tubes being

slidably engaged within the first named tubes, V shaped openings formed at the outer ends of said inner tubular elements, lugs formed at the ends thereof, engageable in said slots, and springs encircling both of said tubular elements adapted to press said guard plates away from said fixed plates.

3. In an anti-submarine device, the combination with a rigid plate surrounding the hull of a ship, of tubular elements secured to the exterior of said rigid plate, said tubular elements containing longitudinal slots, independent rectangular armor plates, tu-

bular elements secured to the inner sides thereof, said tubular elements being engageable within the first named tubular elements, and adapted to operate with lateral resilience, lugs formed on the outer extremities of the second named tubular elements adapted to enter the slots in the second named tubular element, and means adapted to press said movable plate outwardly.

In testimony whereof we have affixed our signatures.

WASIL PAZAYCHUK.
WASYL PATZ.
